DESIGN FOR A SPOON OR ANALOGOUS ARTICLE

Arthur Le Roy Barney, New York, N. Y., assignor to Tiffany & Company, New York, N. Y., a corporation of New York

Application April 25, 1936, Serial No. 62,298

Term of patent 14 years

To all whom it may concern:

Be it known that I, Arthur Le Roy Barney, a citizen of the United States, residing at No. 64 East 86th Street, New York city, New York, have invented a new, original, and ornamental Design for a Spoon or Analogous Article, of which the following is a specification, reference being had to the accompanying drawing, forming a part thereof.

I regard the dominant feature of my design as being in the contour and ornamentation of the handle thereof.

I claim:

The ornamental design for a spoon or analogous article as shown and described.

ARTHUR LE ROY BARNEY.
